UNITED STATES PATENT OFFICE.

WILLIAM ARTER, OF WORCESTER, MASSACHUSETTS.

STARTING AND STOPPING MECHANISM.

Application filed October 27, 1919. Serial No. 333,821.

To all whom it may concern:

Be it known that I, WILLIAM ARTER, a subject of the King of Great Britain, residing at Worcester, in the county of Worcester and State of Massachusetts, have invented 5 certain Improvements in Starting and Stopping Mechanisms, of which the following description, in connection with the accompanying drawings, is a specification, like reference characters on the drawings indicating like parts in the several figures.

This invention relates to starting and stopping mechanisms for machines and is particularly concerned with a mechanism of 15 this type designed to meet the requirements of grinding machines equipped with a rotary chuck supported on a vertical shaft. It is usual to equip machines of this type with some form of clutch to control the rotation of the chuck shaft, and since the 20 rotating parts are very heavy, their momentum will cause them to rotate for a long time after the shaft has been disconnected from its source of power unless some kind of a 25 brake mechanism is provided to stop it. It is the chief object of the present invention to devise a starting and stopping mechanism which will satisfy the peculiar requirements as to space limits in machines of this type, 30 which can be economically manufactured, will not be subject to rapid wear or deterioration, will be reliable in operation, and will be convenient for the workmen to operate. While the invention is directed particularly 35 to the requirements of grinding machine chuck shafts, it will be evident that the mechanism provided by this invention is applicable also to other machines.

The nature of the invention will be readily 40 understood from the following description when read in connection with the accompanying drawings and the novel features will be particularly pointed out in the appended claims.

45 Referring now to the drawings:

Figure 1 is a vertical cross sectional view through those parts of the grinding machine immediately associated with a chuck shaft;

50 Fig. 2 is a side elevation of the parts of a grinding machine adjacent to the chuck, certain of the parts being broken away;

Fig. 3 is a bottom view of the moving parts of the brake mechanism provided by this invention; and

Fig. 4 is a view of certain parts shown in Fig. 3 but showing these parts in a different position.

In the drawings, 2 designates a magnetic chuck mounted on the upper end of a vertical shaft 3, the weight of these parts being supported by conical bearing members 4 and 5. Another bearing 6 guides the lower end of the shaft. These parts are all mounted in a bracket 7 which is supported 60 on a pivot pin 8 carried by a slide 9 that may be adjusted vertically by a suitable elevating mechanism, as will be readily understood by those skilled in this art. The pivotal support of the bracket 7 enables it to be adjusted angularly to suit the nature and requirements of the work.

The bracket 7 is hollowed out to receive a stationary brake sleeve or drum 10 and the inner surface of this drum is machined to 75 co-operate with the peripheral surface of a split brake ring 12, best shown in Fig. 3. From this figure it will be seen that this ring has two concentric ring portions, the outer ring 12 being split to form two end 80 portions *a* and *b*, and the inner portion 14 closely embracing the shaft 3. At what may be termed the front side, the inner and outer sections of the ring are separated by a saw cut 15, while at the rear side these sections 85 are connected by a web 16 which is drilled to receive a set screw 17 by means of which the split ring is secured fast to the chuck shaft 3.

The opposite walls of the split in the ring 90 12 are recessed to receive projections 18 and 19, respectively, that extend upwardly from the respective levers 20 and 21. These levers are curved, as clearly shown in Fig. 3, and have knobs 22 and 23, respectively, secured 95 to their free ends and located at substantially diametrically opposite points where they may be engaged and spread apart by the upper bevelled end of a sleeve 24, Fig. 1, mounted to slide longitudinally of the shaft 100 3. It will be seen from an inspection of Figs. 3 and 4 that the projections 18 and 19 are rounded cylindrical pins cut away to form flattened faces that normally lie in

contact with each other. When the sleeve 24 is moved upwardly and spreads the free ends of the levers 20 and 21, apart, it rocks these faces about their forward edges as a fulcrum, moving them into a position substantially as shown in Fig. 4, and thus spreads the ends *a* and *b* of the friction ring 12 apart expanding this ring into engagement with the inner surface of the stationary brake drum 10. This obviously applies a powerful braking action to the shaft and stops its rotative movement quickly. When the sleeve 24 is lowered again out of contact with the knobs 22 and 23 on the levers 20 and 21, respectively, the ring 12 contracts due to its inherent elasticity, returning to its initial position, as shown in Fig. 3, and thus swings the levers back into the position shown in said figure. This action is aided by a spring 25 which connects the ends *a* and *b* of the split ring.

In order to hold the levers 20 and 21 in their operative positions, a pin 26 is threaded into the inner section 14 of the friction ring 25 and lies in recesses formed in the opposite faces of the parts *a* and *b* and 18 and 19. There is very little tendency for the levers to drop out of their normal positions since the projections 18 and 19 are constantly gripped by the ends *a* and *b* of the split ring, but this slight tendency is effectually resisted by the engagement of these parts with the pin 26.

The sleeve 24 may be moved up and down in any convenient manner, as, for instance, by means of a bifurcated lever arm 27, Fig. 1, carrying rolls that enter a slot 28 forming the periphery of the sleeve 24, the lever being mounted fast on a rock shaft 29 which projects through the housing or casing 30 and has a hand lever 31 fixed thereto at a point outside of said housing.

For the purpose of driving the shaft 3, a gear 32 is mounted loosely thereon, the weight of the gear being supported by a collar 33, Fig. 1, secured to the shaft. This gear is hollowed out to receive a split ring 34, like the ring 12 in construction, which is keyed to the shaft 3 and co-operates with a pair of levers like the levers 20 and 21. One of these levers is indicated in Fig. 1, at 35. These parts form an expanding clutch of exactly the same construction as the expanding brake above described, the only difference being that the expanding clutch ring 34 engages the inner surface of the gear 32, whereas the expanding brake ring 12 engages the inner surface of the brake drum 10. The lower end of the sleeve 24 is bevelled so that it operates on the levers that expand the ring 34 in the same way that it operates on the levers 20 and 21. This arrangement is of advantage in manufacturing and assembling since it reduces the number of kinds of parts required, the

parts of the clutch being duplicates of those of the brake with the exception above mentioned.

It will also be seen that this construction is exceedingly simple to manufacture, that it forms a very effective and reliable construction of brake and clutch, that it can be conveniently operated by a single actuating member, and that it is well adapted for use in the small space limits within which these parts must be located in grinding and similar machines.

It is obvious that many changes may be made in details of the construction shown without departing from the spirit or scope of this invention. For instance, instead of using the brake drum 10 the braking surface could be formed directly in the bracket 7 without in any wise modifying the operation of the mechanism. This, however, is regarded as an equivalent construction.

What is claimed as new is:

1. In a machine of the character described, the combination of a rotatable shaft, a bearing bracket supporting said shaft, a driving gear for said shaft loosely mounted thereon and having a recess therein, an expanding clutch including a clutch member secured to said shaft and located in said recess, a stationary brake drum encircling said shaft and supported by said bracket, an expandable brake comprising a brake member located within said drum and secured to said shaft, operating means for said brake and clutch including a sleeve mounted between said brake and clutch for operating either of them, and means for sliding said sleeve on said shaft.

2. In a machine of the character described, the combination of a rotatable shaft, a bearing bracket supporting said shaft, a driving gear for said shaft loosely mounted thereon and having a recess therein, a split clutch ring fast on said shaft and located within said recess, a pair of levers cooperating with the split in said ring to expand the ring into engagement with the walls of the recess in said gear, said levers having ends lying closely adjacent to said shaft, a sleeve slidable longitudinally of said shaft and having a bevelled end to engage the ends of said levers to operate them and thereby expand said clutch ring, a stationary brake drum encircling said shaft and supported by said bracket, a split brake ring secured to said shaft and mounted within said drum, a second pair of levers like the levers above mentioned arranged to expand said brake ring into engagement with said brake drum and positioned to be operated by said sleeve, and means for sliding said sleeve longitudinally of said shaft.

In testimony whereof I have signed my name to this specification.

WILLIAM ARTER.
